UNITED STATES PATENT OFFICE.

PATRICK MIHAN, OF CHELSEA, MASSACHUSETTS.

VENTILATOR FOR SHIPS.

SPECIFICATION forming part of Letters Patent No. 257,507, dated May 9, 1882.

Application filed January 23, 1882. (No model.)

To all whom it may concern:

Be it known that I, PATRICK MIHAN, of Chelsea, in the county of Suffolk, of the State of Massachusetts, have invented a new and useful Improvement in Ventilators; and I do hereby declare the same to be described in the following specification and represented in the accompanying drawings, of which—

Figure 1 is a side view; Fig. 2, a front elevation. Fig. 3 is a longitudinal and transverse section of a ventilator of my improved kind. Fig. 4 is a transverse section of its lower deflector and its water intercepting and discharging gutters.

15 The ventilator is intended principally for use on shipboard for ventilating the cabin or other part of a navigable vessel, although it may be employed to advantage on dwellings or various other structures on land.

20 The nature of my invention is set forth in the claims hereinafter presented.

The said ventilator consists in part of a hood, A, having on one side of it a mouth, a, of a rectangular or other suitable form, and also having within and across it the said hood, and in rear of and arranged with the mouth, as represented, a partition, b. The ventilator, as represented, further consists of two deflectors, B C, one of which—viz., the lower, C, of them—is hinged at its upper part to the lower part of the partition b, the upper deflector, B, being hinged to the partition on or about on a level with the top of the mouth a. The lower deflector, when down or closed, inclines toward and rests upon the lower edge of the mouth, so the upper deflector, when up or closed, rests against the upper edge of the said mouth.

At its back the lower deflector is provided with a lip or flange, c, to extend from it upward in rear of and against the partition b, such lip, when the deflector is closed, serving to prevent any water on the deflector from passing underneath the partition and thence down into the space below it. Furthermore, the deflector C, at each side edge, has a lip or flange, d, projecting down from it over or into one of two inclined gutters, e, arranged on the inner side of the hood, and leading to and through the lower corners of its mouth. There is also 45 to the outer edge of the said deflector a lip or flange, f, to close and extend below the lower edge of the mouth when the deflector is closed.

This flange or top is to prevent water from being driven between the deflector and the said lower edge when the deflector is closed. The 55 gutters intercept and convey out of the ventilator any water that may pass laterally off the upper surface of the deflector. The deflector C may be made without the lips f and d; but it is preferable to have them, as they serve as 60 additional means of preventing water from working into the ventilator.

There is attached to the upper deflector, B, a chain, cord, or rope, g, which, after being led partially around two guide-wheels, h i, arranged in 65 the hood in the manner as represented, is connected to a rod, k, adapted to slide vertically within the duct l surmounted by the hood. A small pan or vessel, m, is attached to the rod k at its lower end, such pan being arranged directly over or within a tunnel, n, having its discharge-pipe o furnished with a damper or closing-valve, p, and arranged to carry off any 70 water that may fall into the tunnel. The upper deflector is to be of sufficient weight, or is 75 to be weighted for it in falling to raise the pan.

Should a sea strike the ventilator, and water thereby be caused to flow upward into the hood and over the top of the partition b, such water will drop into the pan, and by its weight 80 will cause the pan to descend and lift up and suddenly close the upper deflector in order to stop the inflow of water. On the pan thus descending a valve, r, to an opening, s, in the 85 bottom of the pan will be opened by a projection, t, from such valve being carried against the tunnel, in which case the water in the pan will be discharged from it until the upper deflector may drop down and lift the pan.

While the weather is fair or pleasant the 90 lower deflector is to be kept raised up to the top of the mouth a, in which case air or wind blown against the lower surface of the deflector will be deflected thereby downward into the hood, and thence down its duct l; but 95 during bad or stormy weather the lower deflector is to be closed, in which case air on being blown against the inclined upper surface of the said deflector will be deflected thereby upward into the hood and over the partition 100 b, and by the curved top of the hood will be turned down into and through the hood, a stay or plate, v, arranged in the hood in manner as shown, serving to support one of the

journals in which one of the guide-wheels *h* *i* turns.

I would remark that the ventilator may be used to advantage without the upper deflect- 5 or—in other words, that such deflector may be dispensed with; but it is preferable to have it. I would also remark that the gravitating pan may also be omitted in some cases, the rod and line or cord for supporting such pan 10 being then employed to enable a person by pulling on the rod to raise the upper deflector partially or entirely upward, as occasion may require, such deflector being not only to prevent water from being blown or driven up- 15 ward into the hood, but to regulate the inflow of air.

My invention differs very materially from the car-ventilator shown and described in the United States Patent No. 13,779 to Corbett, 20 which is a horizontal duct provided with two flaring mouths, and with two valves and an intermediate vertical duct. In my ventilator the duct is vertical and has but one mouth, a vertical partition arranged in rear of it, and 25 to extend above it within the case, and it also has its deflector C hinged to the partition so as to be movable up to the top or down to the bottom of the mouth.

What I claim as my invention in the afore- 30 described ventilator is as follows, viz:

1. The ventilator - hood provided with the single mouth *a*, and with partition *b*, deflector *C*, adapted and arranged and to operate there- with, substantially as set forth.

2. The ventilator-hood provided with the 35 single mouth *a*, and with partition *b*, and the two deflectors *B* and *C*, adapted and arranged and to operate therewith, substantially as set forth.

3. The hood provided with the inclined gut- 40ters *e*, and with the deflector *C*, and partition *b*, arranged with the mouth *a* of the said hood, substantially as set forth.

4. The deflector *C*, provided with the rear 45 lip or flange, *c*, in combination, and arranged as described, with the hood and its mouth and partition *b*, disposed as shown.

5. The deflector *C*, provided with the side 50 lips, *d*, in combination, and arranged as de- scribed, with the hood and its mouth *a*, parti- tion *b*, and gutters *e*, disposed as represented.

6. The deflector *C*, provided with the front 55 lip, *f*, in combination, and arranged as de- scribed, with the hood and its mouth *a* and partition *b*, disposed as represented.

7. The combination of the water-intercept- 60 ing pan *m*, provided with the discharge-valve, as described, with the tunnel *n*, and with a ventilator-hood provided with a mouth, *a*, par- tition *b*, and the two deflectors *B* and *C*, all being adapted and arranged to operate in man- 65 ner and for the purposes substantially as set forth.

PATRICK MIHAN.
